UNITED STATES PATENT OFFICE.

FRANK SHUMAN, OF PHILADELPHIA, PENNSYLVANIA.

CONCRETE PILE AND METHOD OF MAKING THE SAME.

No. 805,936.

Specification of Letters Patent.

Patented Nov. 28, 1905.

Application filed January 9, 1905. Serial No. 240,289.

To all whom it may concern:

Be it known that I, FRANK SHUMAN, a citizen of the United States, residing in Philadelphia, Pennsylvania, have invented certain improvements in Concrete Piles and in the Formation of the Same, of which the following is a specification.

The object of my invention is to provide an extremely-strong concrete pile intended especially for use in the construction of wharves, docks, or other work which is partly under water or in unstable ground, although the pile is also available for general use, if desired.

In the accompanying drawings, Figure 1 is a longitudinal sectional view of a pile constructed in accordance with my invention. Figs. 2, 3, and 4 are views illustrating successive stages in the formation of said pile. Fig. 5 is a sectional plan view on the line *a a*, Fig. 1; and Fig. 6 is a sectional plan view on the line *b b*, Fig. 1.

The pile shown in Fig. 1 may form part of a wharf or other structure, the upper portion of the pile, which is within and above the water and in the unstable portion of the bottom of the waterway, being of lesser diameter than the lower portion of the pile, which is contained in the stable ground, said contracted upper portion of the pile being provided with a casing 1, of sheet metal or other available material, which serves during the formation of the pile to confine the mass of concrete constituting the upper portion of the same and which also serves as a permanent or temporary sheathing for said upper portion of the completed pile. Within the contracted upper portion of the pile and also extending down into the enlarged lower portion of the same to any desired extent is a metallic reinforce consisting in the present instance of a tubular cage composed of vertical rods 3, connected together at suitable intervals by means of wire rings 4, engaging said rods, although other forms of metallic reinforce may, if desired, be used in carrying out my invention. For instance, a tube composed of woven wire or of the material known as "expanded metal" may be employed.

In forming a concrete pile in accordance with my invention I may use a hollow preparatory pile having either a valved lower end or a detachable point to the left in the bottom of the opening formed by said preparatory pile or a removable point to be withdrawn

through the pile, so that as said hollow preparatory pile is withdrawn from the opening formed thereby the concrete of which the permanent pile is to be composed can be fed into the opening through the pile. In 60 the present instance I have shown the hollow preparatory pile 5 as provided with a valved point consisting of pivoted and swinging members 6, which when closed form a tapering point on the pile, the valved members occupying this position during the driving of the preparatory pile, as shown in Fig. 2.

After the preparatory pile has been driven to the proper depth the same is slowly or intermittently withdrawn and the concrete is 70 fed through the same while it is being withdrawn, the members of the valved point swinging open, as shown in Fig. 3, in order to permit of the passage of the concrete between them.

When that point in the formation of the pile is reached at which the metallic reinforce is to be inserted, said reinforce is properly located within the hollow preparatory pile, and the withdrawal of the latter is proceeded with, the concrete being now fed in through the metallic reinforce, the meshes or openings of which are large enough to permit of the passage of the concrete laterally through them, so that as the formation of the 85 pile proceeds the metallic reinforce will be embedded in the mass of concrete, as shown in Fig. 4.

When the formation of the pile approaches the unstable ground constituting the bottom 90 of the waterway, the sheet-metal tube or casing 1 is inserted into the preparatory pile, as shown in Fig. 4, so that it will retain the concrete during the further withdrawal of the preparatory pile and during the building of 95 the pile above the level of the bottom of the waterway the casing also constituting, if desired, a sheathing for the upper portion of the finished pile.

If desired, the casing 1 may be secured in 100 any suitable manner to the reinforcing structure 3 and inserted with the latter.

Where the pile is formed in stable ground, the use of the casing 1 will not be necessary, although such use may even in this case be 105 advisable.

Other means of forming in the ground the opening for the reception of the permanent pile may also be adopted within the scope of my invention. For instance, the prepara- 110

tory pile may be open at the lower end and may be sunk in the ground by washing or otherwise removing the earth from within the pile, the formation of the concrete pile 5 after the sinking of such preparatory pile proceeding in the manner before described, or where the pile is to be formed in stable ground the preparatory pile may be completely removed from the opening before the 10 filling in of the concrete, the metallic reinforcement being introduced either before or after the withdrawal of the preparatory pile, as desired, and where the preparatory pile is removed before filling in the concrete the preparatory pile need not be hollow and need 15 not have a valved or removable point.

As the upper portion of the pile only serves to transmit strains to the lower or embedded portion, it is not necessary that said upper 20 portion should be as heavy as the lower portion. Hence I am enabled to effect a considerable saving in the amount of concrete necessary for the construction of the pile.

Having thus described my invention, I 25 claim and desire to secure by Letters Patent—

1. The mode herein described of making a concrete pile, said mode consisting in first driving or sinking a preparatory pile, then 30 withdrawing the same and introducing concrete into the opening formed thereby, and, before or during such introduction of the concrete, inserting a metallic reinforce into the opening, substantially as specified.

35 2. The mode herein described of making a concrete pile, said mode consisting in first driving or sinking a hollow preparatory pile, then slowly or intermittently withdrawing the same, and, during such withdrawal, introducing the concrete into the opening formed by the pile, and, before or during the introduction of the concrete, inserting a metallic reinforce into said opening, substantially as specified.

40 3. The mode herein described of forming a concrete pile, said mode consisting in first driving into the ground a hollow preparatory pile having a movable point, then slowly or intermittently withdrawing said preparatory 45 pile, and, during such withdrawal, introducing concrete into the opening formed thereby, and, before or during the introduction of the concrete, inserting a metallic reinforce into the opening, substantially as specified.

50 55 4. The mode herein described of forming a concrete pile, said mode consisting in first driving or sinking a preparatory pile, then withdrawing the same and introducing concrete into the opening formed thereby, and, before or during such introduction of the concrete, inserting into the opening a tubular metallic reinforce having openings through 60 which the concrete can pass laterally so as to embed the reinforce therein, substantially 65 as specified.

5. The mode herein described of forming a concrete pile, said mode consisting in first driving or sinking a hollow preparatory pile, then slowly or intermittently withdrawing the same, and, during such withdrawal, introducing concrete into the opening formed thereby, and, before or during such introduction of the concrete, inserting into the opening a tubular metallic reinforce, having openings for the lateral passage of the concrete, substantially as specified. 70

6. The mode herein described of forming a concrete pile, said mode consisting in first driving a hollow preparatory pile having a movable point, then slowly or intermittently withdrawing said preparatory pile, and, as it is being withdrawn, introducing concrete through the same into the opening formed by it, and, before or during such introduction of the concrete, inserting into the opening a tubular metallic reinforce having openings through which the concrete can pass laterally so as to embed the reinforce therein, substantially as specified. 80

7. The mode herein described of forming a concrete pile, said mode consisting in first driving or sinking a hollow preparatory pile, then slowly or intermittently withdrawing the same, and, during such withdrawal, introducing concrete through the hollow pile 90 into the opening formed thereby, inserting a metallic reinforce into the hollow preparatory pile after the same has been partially withdrawn and then continuing such withdrawal and the introduction of the concrete, so as to embed the metallic reinforce therein, substantially as specified. 95

8. The mode herein described of forming a concrete pile, said mode consisting in first driving a hollow preparatory pile having a movable point, then slowly or intermittently withdrawing said pile, and, as it is being withdrawn, introducing concrete through it into the opening formed by it, inserting a metallic reinforce into the hollow pile after the same has been partially withdrawn and then continuing such withdrawal, and the introduction of the concrete so as to effect the embedding of the metallic reinforce in the latter, substantially as specified. 105

9. The mode herein described of forming a concrete pile, said mode consisting in first driving or sinking a hollow preparatory pile and then slowly or intermittently withdrawing the same, and, as it is being withdrawn, introducing concrete through the same into the opening which it has formed, introducing into the hollow preparatory pile, after the partial withdrawal of the same, a tubular metallic reinforce having openings through which the concrete can escape laterally, and then continuing the withdrawal of the hollow preparatory pile and introducing the concrete through said tubular metallic reinforce, substantially as specified. 115 120 125 130

10. The mode herein described of forming a concrete pile, said mode consisting in first driving a hollow preparatory pile having a movable point, then slowly or intermittently withdrawing said pile, and, as it is being withdrawn, introducing concrete through it into the opening which it has formed, introducing into the preparatory pile, after it has been partially withdrawn, a tubular metallic reinforce having openings through which the concrete can escape laterally, and then continuing the withdrawal of the pile and introducing the concrete through said tubular metallic reinforce, substantially as specified. 65
15. 11. The mode herein described of forming a concrete pile, said mode consisting in driving or sinking a hollow preparatory pile, then partially withdrawing said pile and filling concrete through it into the opening which it has formed, then introducing into the hollow preparatory pile, a casing or sheathing structure and then continuing the withdrawal of the hollow preparatory pile and filling the remainder of the concrete into said casing or sheathing structure, substantially as specified. 70
20. 12. The mode herein described of forming a concrete pile, said mode consisting in first driving or sinking a hollow preparatory pile, then partially withdrawing the same and introducing concrete through it into the opening which it has formed, and, before or during such introduction of the concrete, inserting into the hollow preparatory pile a metallic reinforce and a casing or sheathing structure and then completing the withdrawal of the preparatory pile and filling in the remaining concrete through said casing or sheathing structure, substantially as specified. 75
25. 13. The mode herein described of forming a concrete pile, said mode consisting in first driving or sinking a hollow preparatory pile, then partially withdrawing the same and introducing concrete through it into the opening which it has formed, and, before or during such introduction of the concrete, inserting into the hollow preparatory pile a casing or sheathing structure, and a tubular metallic reinforce having openings through which the concrete can escape laterally, and then completing the withdrawal of the preparatory pile, and filling in the remaining concrete through said casing or sheathing structure and the tubular metallic reinforce, substantially as specified. 80
30. 14. The mode herein described of forming a concrete pile, said mode consisting in driving a hollow preparatory pile having a movable point, then partially withdrawing said pile and filling concrete through it into the opening which it has formed, then introducing into the hollow preparatory pile a casing or sheathing structure, and then completing the withdrawal of the hollow preparatory pile and filling in the remaining concrete through said casing or sheathing structure, substantially as specified. 85
35. 15. The mode herein described of forming a concrete pile, said mode consisting in first driving a hollow preparatory pile having a movable point, then partially withdrawing said pile and introducing concrete through it into the opening which it has formed, and, before or during such introduction of the concrete, inserting into the hollow preparatory pile a metallic reinforce and a casing or sheathing structure, and then completing the withdrawal of the preparatory pile and filling in the remaining concrete through said casing or sheathing structure, substantially as specified. 90
40. 16. The mode herein described of forming a concrete pile, said mode consisting in first driving or sinking a hollow preparatory pile, then partially withdrawing the same and introducing concrete through it into the opening which it has formed, then inserting a metallic reinforce into the hollow pile, continuing the withdrawal of the same and filling in the concrete so as to embed the metallic reinforce therein, then inserting a casing or sheathing structure into the hollow pile, completing the withdrawal of the same and filling the remaining concrete into said casing or sheathing structure, substantially as specified. 95
45. 17. The mode herein described of forming a concrete pile, said mode consisting in first driving or sinking a hollow preparatory pile, then partially withdrawing the same and introducing concrete through it into the opening which it has formed, then inserting into the hollow pile a tubular metallic reinforce having openings through which the concrete can escape laterally, then continuing the withdrawal of the pile and introducing the concrete through said tubular metallic reinforce, then inserting a casing or sheathing structure into the hollow pile, and then completing the withdrawal of said pile and filling the remaining concrete into said casing or sheathing structure, substantially as specified. 100
50. 18. A concrete pile having its lower portion of greater diameter than the upper portion and having a metallic reinforce contained in said contracted upper portion of the pile and extending down into the lower portion of the same, substantially as specified. 105
55. 19. A concrete pile having its lower portion of greater diameter than the upper portion and having a metallic reinforce contained in said contracted upper portion of the pile and extending part way into the expanded lower portion of the pile, substantially as specified. 110
60. 20. A concrete pile having its lower portion of greater diameter than its upper portion and having embedded in said upper portion a tubular metallic reinforce which extends down into the lower portion of the pile, substantially as specified. 115
65. 120
70. 125

21. A concrete pile having its lower portion of greater diameter than its upper portion, said upper portion having a casing or sheathing and an internal metallic reinforce, 5 substantially as specified.

22. A concrete pile having its lower portion of greater diameter than its upper portion, said upper portion having a casing or sheathing and an internal metallic reinforce, 10 consisting of a tubular structure with openings therein for the reception of the concrete, substantially as specified.

23. A concrete pile having an internal metallic reinforce and an external casing or 15 sheathing which extends throughout only

the upper portion of the pile, substantially as specified.

24. A concrete pile having a tubular metallic reinforce embedded therein, and having an external casing or sheathing which extends throughout only the upper portion of the pile, substantially as specified. 20

In testimony whereof I have signed my name to this specification in the presence of two subscribing witnesses.

FRANK SHUMAN.
